2 SHEETS—SHEET 2.

UNITED STATES PATENT OFFICE.

JOHN J. NEVILLE, OF CLIFTON FORGE, VIRGINIA.

ORE-SEPARATOR.

1,391,400.

Specification of Letters Patent. Patented Sept. 20, 1921.

Application filed June 18, 1921. Serial No. 478,704.

To all whom it may concern:

Be it known that I, JOHN J. NEVILLE, a citizen of the United States, residing at Clifton Forge, in the county of Alleghany and State of Virginia, have invented certain new and useful Improvements in Ore-Separators, of which the following is a specification, reference being had to the accompanying drawings.

10 This invention relates to ore separators, and particularly to separators for separating iron ore from non-magnetic materials or magnetism.

In southwestern Virginia there are large 15 deposits of iron ore wherein the iron is aggregated with flint nodules and standstone. This ore is very refractory and difficult to treat at a profit, though there are large quantities of the ore in this section of the country.

20 The object of the present invention is to provide means for treating ore of this character by crushing the ore finely and then submitting the ore to the action of a plurality of magnets, these magnets drawing the particles of iron from the crushed mass but permitting the sand to pass over.

A further object is to provide an improved 30 construction for this purpose including a drum having thereon a series of electro-magnets, the drum rotating above a conveyer belt, the electro-magnets being energized each as it passes over the belt to pick up particles of iron therefrom, and the several 35 magnets being deenergized when above a chute so that the particles of iron will fall into the chute and be discharged.

And a further object is to form the belt or conveyer of or with a series of electro-magnets which travel with the belt or conveyer and which are normally deenergized but which are energized after the drum has acted upon the ore and as the conveyer passes from its upper flight to its lower flight so that as the conveyer passes from its upper 45 flight to its lower flight and travels along the lower flight, the particles of iron ore will remain attached to the magnets or conveyer while the particles of sand or other foreign matter will drop therefrom, the 50 magnets of the conveyer being then deenergized to cause the dropping of the particles of iron.

Still another object is to provide a second magnet disposed below the endless carrier 55 and rearward of the point where the carrier

is deenergized, this second magnet being in the form of a drum and acting upon the particles which have been dropped from the conveyer to separate the iron ore from the other foreign matter. 60

Another object is to provide a construction of this character including a supporting frame, a stone crusher mounted at one end of the frame, an endless conveyer upon which the stone crusher discharges, a distributor for distributing the crushed ore in a thin sheet over the traveling conveyer, and provide at the opposite ends from the ore crusher the magnetically acting means heretofore referred to whereby the iron is 65 separated from the other minerals. 70

Other objects will appear in the course of the following description.

My invention is illustrated in the accompanying drawings, wherein:— 75

Figure 1 is a side elevation partly broken away of an ore separator constructed in accordance with my invention;

Fig. 2 is a top plan view thereof;

Fig. 3 is an elevation of one end of the 80 drum and of the contact strip 29 coacting therewith, showing diagrammatically the electrical connections;

Fig. 4 is a fragmentary transverse section through the drum and the contact 85 strip 29;

Fig. 5 is a section on the line 5—5 of Fig. 4;

Fig. 6 is a transverse section through the drum as in Fig. 4 but showing another 90 manner of forming the magnets;

Fig. 7 is a fragmentary transverse section through the drum 26 and contact strip therefor;

Fig. 8 is a fragmentary transverse section through the endless element 18 showing the magnets thereon and the means whereby these magnets are electrically energized. 95

Referring to these drawings, 10 designates the frame of the machine which may be of any suitable construction and which supports at one end the ore crusher 11. This ore crusher is driven by an electric motor 12, whose shaft 13 is connected either directly or indirectly to the gearing of the 105 ore crusher. The ore crusher may be of any suitable character and I have not illustrated any details thereof. The ore crusher discharges onto a chute 14 supported by the frame. At the rear end of the frame there 110

is disposed a roller 15 which may be driven in any suitable manner but which is illustrated as being driven by a belt 16 from a belt wheel on the shaft 13. At the other 5 extremity of the frame there is disposed a roller 17, and over these two rollers travels the endless carrier 18. This endless carrier is formed preferably as will be later stated.

10 Mounted in suitable bearings at the discharge end of the machine is a drum 19 having upon its face a series of electro-magnetically energized, flat, transversely extending strips or bars 20. These bars or 15 strips are made of soft iron and may be magnetized in a number of different ways, as will be later stated. This electro-magnet operates in a direction reverse to that of the belt, that is in a counter-clockwise direction, and the magnets are intermittently 20 energized and de-energized so that as the drum rotates above the belt the particles of iron on the belt will be picked up by the magnets on the rotating drum, carried upward and over toward the front of the machine 25 and then discharged into a chute 21. Preferably a distributor in the form of a transversely extending blade 22 is mounted upon the frame of the machine between the chute 14 and the drum 19 so as to cause the finely powdered or ground-up material 30 to be distributed in a thin sheet or layer over the face of the conveyer or carrier. Preferably the conveyer 18 carries upon 35 it a series of electrically magnetized plates or strips 36 of soft iron which are intermittently magnetized or de-magnetized, as will be later described, and these strips are magnetized from the point *a* to the point *b* 40 as they travel around the roller 17 so that at the time when the magnets on the drum 19 act upon the particles of ore, the magnetic strips on the conveyer or carrier are de-magnetized. After the drum has acted 45 upon the material, the magnets 23 are energized so that as the conveyer passes around the roller 17 the non-magnetic particles will fall from the conveyer and be discharged onto a chute 24, while the magnetic particles 50 will cling to the conveyer and remain clinging thereto until the magnets of the conveyer are de-magnetized, whereupon the particles will drop, as for instance into a chute 25. The magnets on the drum 19 and 55 the magnets on the endless carrier will not possibly attract all of the particles of iron ore which may be in the material and, therefore, I submit the material passing down the chute 24, from which most of the magnetic particles have been separated, to the 60 action of a third set of magnets carried on a drum 26, this drum picking up the magnetic particles from the material passing along the chute 24 and carrying these particles over and dropping the particles upon

the chute 25, the magnets of the drum 26 being intermittently magnetized and de-magnetized, as will be later explained.

It will thus be seen that by providing a plurality of magnets, I submit the crushed ore to the action of a number of magnets so as to remove from this ore as much as possible of the magnetic material which may be therein, and furthermore I do this positively, not by merely deflecting the magnetic particles of ore to one side but by picking up these magnetic particles and transporting them to the place desired and then by de-energizing the magnets causing the particles to drop off. It will be understood 70 that brushes might be provided, as at 27, which will dislodge the magnetic particles which might chance to adhere to the magnets either by residual magnetism or in any other way. 85

I do not wish to be limited to any particular means for forming the electro-magnets on the drums 19 or 26 or on the endless conveyer 18. I have illustrated, however, two ways in which these magnets might be energized and de-energized. I have illustrated the magnets for the drum 19 as being T-shaped in cross section to provide the transversely extending strips or plates 20 and coils 28, each core being provided with a 95 magnetic coil 29. Obviously when a current of electricity flows through the magnetic coil, the core and the corresponding strip 20 will be rendered magnetic and obviously when the current ceases to flow through the 100 coil, the core and strip 20 will be de-energized.

For the purpose of energizing the magnets 20 from the point *c* to the point *d*, I have shown an arcuate conducting strip 29 105 (Fig. 3) mounted upon the frame of the machine to one side of the drum and extending from the point *c* to the point *d*. This conducting strip is connected to a source of current, as for instance to the positive pole of 110 a battery 30 or any other suitable source. The opposite end of each coil 28 may be grounded. Each coil is engaged at one end with an outwardly projecting pin or contact 31 which engages the strip 29 and keeps 115 its engagement with this strip while this pin is traveling from the point *c* to the point *d*. During this period therefore the current is traveling through the coil 28 and the electro-magnet is energized. When, however, 120 the pin 31 passes the contact strip 29, the magnet becomes de-energized. Some residual magnetism, however, will remain in the magnet which might be sufficient to cause the particles to adhere thereto and, therefore, 125 it is best to momentarily cause current to pass through the electro-magnets in an opposite direction to the direction of passage of the current while the pins were in contact with the strip 29, and to this end I mount in 130

the path of travel of the pins and just forward of the end of the strip 29 a contact 32 with which each pin will momentarily contact, this contact 32, however, being connected to the negative pole of the battery so as to cause a momentary reversal of the current through the coils. This reverse current is merely momentary and acts to de-magnetize the magnets.

10 Another construction which might be used for forming the magnets is illustrated in Fig. 6, where the strips 23 are connected at their ends to cores 33 and surrounded by coils 34, these coils 34 being in turn connected to a common ground at one end and to pins 35 at the opposite end which are adapted to engage the strips 29. Here also the strips 23 will be rendered magnetic as the pins 35 come in contact with the strip 29 and will become de-magnetized when the pins 35 pass the strip 29. The same means as heretofore described may be used for causing a momentary reversal of current through the magnets if desired.

25 The endless conveyer 18 will also have magnetic strips or plates 36 applied thereto, these strips being substantially T-shaped in cross section and provided with coils 34. These magnetic strips are de-magnetized for the greater portion of travel of the endless conveyer, but each strip is magnetized from the point *a* to the point *b* by means of a contact member 37 which extends around the shaft upon which the roller 17 is mounted and extends at its ends parallel to the upper and lower flights of the endless conveyer. Preferably this contact will be U-shaped in cross section so as to permit the pins 38, which are connected to the several strips, to pass between the upper and lower webs of the contact 37 and thereby secure a perfectly good electrical engagement between the contact strip 37 and the pins 38.

30 Preferably, and as illustrated in Fig. 8, these strips 36 are mounted at their ends upon longitudinally extending belts 39. The downwardly extending web of each strip is cut away, as at 40, at the middle of the strip to accommodate a sprocket chain 41. This sprocket chain is not attached to the strips but engages a sprocket wheel 42 on the shaft of roller 17, which is smaller in diameter than the roller, and disposed between the two sections of the roller, this sprocket chain 45 passing over a driving sprocket wheel 43 on the shaft of drum or roller 15, thus transmitting power from the drum or roller 15 to the roller 17 without putting any strain upon the conveyer belt formed of the strips 36 and the bands 39. Preferably the strips 36 will be spaced from each other by intervening strips of insulating material, designated 44.

35 The drum 26 has magnetic strips applied thereto of the same character as those ap-

plied to the drum 19 and these strips are magnetized by contact of the pins on the strips and with a contact strip 38 in the manner heretofore described.

40 It will be obvious now that the crushed ore falling upon the endless carrier 18 will be distributed thereover in a thin sheet by means of the distributor 22, and that when the conveyer carries this crushed ore beneath the drum 19, the particles of iron ore 45 from the conveyer will be picked up, carried over on the drum and discharged over onto the chute 21, while the other particles not picked up by the magnetic drum will be carried along by the magnetic strips on the endless conveyer which at this time have become magnetized, carried around the roller 17 and onto the point *b* where the strips being demagnetized, the particles of iron fall off onto the chute 25. The particles which may 50 fall off from the belt as it passes around the roller 17 to the point *b* fall onto the chute 24 and are carried beneath the second drum 26 which picks up any magnetic particles and in turn discharges them onto the chute 55 25, while the thoroughly separated, non-metallic particles pass down the chute 24 and are discharged. As before remarked, I do not wish to be limited to the particular manner of forming the electro-magnets or 60 the particular manner of causing these electro-magnets to become energized and de-energized.

65 This combined separator and crusher may be portable so that it may be carried to any 100 desired point where the ore is being mined so that the ore may be crushed at the point where it is being mined and the iron separated from the non-magnetic particles so that only the natural iron ore may be transported to the smelter or other place of final treatment. At the present day it is necessary to transport the ore, which includes 105 large masses of non-magnetic materials, from the mine to the smelter, thus adding 110 very greatly to the cost of production.

70 I have illustrated the shaft of the roller 17 as carrying band wheels whereby the drums 19 and 26 may be rotated. I do not wish to be limited to this, as obviously they 115 may be driven in any desired manner from the motor driven shaft 13.

75 I claim:—

1. An ore separator of the character described including a supporting frame, an 120 endless carrier traveling thereon and supporting a plurality of transversely extending electro-magnets disposed in proximity to each other and each provided with a projecting contact, a drum disposed above the path 125 of travel of the carrier and in proximity thereto and carrying a plurality of electro-magnets mounted thereon, means for energizing the electro-magnets of the drum from a point immediately above the carrier to a 130

point where the electro-magnets are moving downward and forward, and means for energizing the electro-magnets of the carrier from a point on the upper flight of the carrier forward of the drum to a predetermined point on the lower flight of the carrier to thereby cause magnetic particles not acted upon by the drum to be held to the carrier for a predetermined distance as it traverses its lower flight.

2. An ore separator of the character described including a supporting frame, an endless carrier traveling thereon and supporting a plurality of transversely extending electro-magnets disposed in proximity to each other and each provided with a projecting contact, a drum disposed above the path of travel of the carrier and in proximity thereto and carrying a plurality of electro-magnets mounted thereon, means for energizing the electro-magnets of the drum from a point immediately above the carrier to a point where the electro-magnets are moving downward and forward, means for energizing the electro-magnets of the carrier from a point on the upper flight of the carrier forward of the drum to a predetermined point on the lower flight of the carrier to thereby cause magnetic particles not acted upon by the drum to be held to the carrier for a predetermined distance as it traverses its lower flight, a chute below the carrier upon which

the non-magnetic particles are discharged, and a second rotatable drum mounted in proximity to said chute, electro-magnets thereon, and means for causing the energizing of said magnets as they come into proximity to the chute and deenergizing said magnets to discharge the magnetic particles adhering thereto.

3. In an ore separator, an endless carrier, rollers over which the endless carrier passes, one of said rollers being power driven, the endless carrier comprising two spaced, longitudinally extending belts, transversely extending, metallic, magnetizable strips attached to the belts at their ends and having cores extending inward, each core being cut away at its middle, electro-magnetic coils surrounding said cores and terminating each in a laterally projecting pin, an electrically energized contact strip with which said pins are adapted to successively engage whereby to cause the magnetization of the strips, said rollers being made in two spaced sections, sprocket wheels mounted between the sections of the rollers, and a sprocket chain connecting said sprocket wheels and thereby forming a driving means between the said rollers.

In testimony whereof I hereunto affix my signature.

JOHN J. NEVILLE.
